UNITED STATES PATENT OFFICE.

WILLIAM A. FRETWELL, OF WILSON, NORTH CAROLINA.

FIRE-ALARM.

1,077,966.

Specification of Letters Patent.

Patented Nov. 4, 1913.

Application filed April 19, 1913. Serial No. 762,307.

To all whom it may concern:

Be it known that I, WILLIAM A. FRETWELL, a citizen of the United States, residing at Wilson, in the county of Wilson and State of North Carolina, have invented a new and useful Fire-Alarm, of which the following is a specification.

The object of this invention is to produce a cheap, infallible alarm that nothing will 10 explode but fire, and to make a ratproof alarm, that rats, roaches nor any vermin can destroy, a perfectly sealed alarm that will fill its mission as long as kept dry. I attain this object by the device illustrated in 15 the accompanying drawing.

Similar letters refer to similar parts.

(A) is a rimfire, cap or fuse ignition cartridge shell containing a powder charge having a wad thereon, leaving a space (B) between the wad and crimped end of the shell. 20 (D) is the cap or fuse end. (E E) are nails or screws driven through the ends of the woven wire envelop (F) to hold the invention to the inside or under houses. This cartridge 25 (A) without my improvement would not

give a sufficient detonation, to be used as a fire-alarm or desired as such but my invention or improvement trebles at least the detonation, and my improvement is simply this, I fill the space (B) with putty, or wax, 30 or plaster of Paris, or concrete dough. When this hardens, the detonation is very much more than the cartridge without it.

These sealed cartridges are inclosed in a woven wire receptacle, and tacked up under 35 and inside buildings by the nails or screws (E E) as a fire alarm.

Having described my invention what I claim as new and wish to secure by Letters Patent, is—⁴⁰

A cartridge having its front end closed by a plastic, such as putty, wax, plaster of Paris or concrete dough, and inclosed in a woven wire receptacle, as a fire alarm, as shown.

WM. A. FRETWELL.
